[57] CLAIM

The ornamental design for a railing junction, as shown and described.

DESCRIPTION

FIG. 1 is a top plan view of a railing junction showing my new design;

FIG. 2 is a front elevational view thereof;

FIG. 3 is a left side elevational view thereof;

FIG. 4 is a right side elevational view thereof;

FIG. 5 is a bottom plan view thereof;

FIG. 6 is a rear elevational view thereof;

FIG. 7 is a perspective view thereof;

FIG. 8 is a top plan view of a second embodiment of a railing junction showing my new design;

FIG. 9 is a front elevational view thereof;

FIG. 10 is a left side elevational view thereof;

FIG. 11 is a right side elevational view thereof;

FIG. 12 is a bottom plan view thereof;

FIG. 13 is a rear elevational view thereof;

FIG. 14 is a perspective view thereof;

FIG. 15 is a top plan view of a third embodiment of a railing junction showing my new design;

FIG. 16 is a front elevational view thereof;

FIG. 17 is a left side elevational view thereof;

FIG. 18 is a right side elevational view thereof;

FIG. 19 is a bottom plan view thereof;

FIG. 20 is a rear elevational view thereof; and,

FIG. 21 is a perspective view thereof.
